UNITED STATES PATENT OFFICE.

NAPOLEON J. PERRY, OF NASHVILLE, TENNESSEE, ASSIGNOR TO MAY HOSIERY MILLS, OF NASHVILLE, TENNESSEE, A CORPORATION OF TENNESSEE.

KNITTING MACHINE.

Application filed December 19, 1919, Serial No. 345,956. Renewed May 29, 1925.

To all whom it may concern:

Be it known that I, NAPOLEON J. PERRY, a citizen of the United States, residing at Nashville, in the county of Davidson and 5 State of Tennessee, have invented certain new and useful Improvements in Knitting Machines, of which the following is a specification.

This invention relates to knitting machines, and has for an object to provide 10 a new and improved type of dial cam head.

A further object of the invention is to provide a dial cam head having cams movable and adjustable therein in improved 15 manner, whereby the dial needles may be moved varying distances for knitting purposes, and also at predetermined intervals advanced for stripping.

With these and other objects in view, the 20 invention comprises certain novel units, combinations and arrangements of parts as will be hereinafter more fully described and claimed.

Referring to the accompanying drawings, 25 which are made a part hereof, and on which similar reference characters indicate similar parts,

Figure 1 is a view of the cam head in inverted plan with the cams shown in knitting 30 position,

Figure 2 is a view in inverted plan showing the knitting cam moved inwardly to withdraw the needles from knitting position,

Figure 3 is a view of the cam head in 35 side elevation as indicated by arrow 3 at Figures 1 and 2, and

Figure 4 is a detail view in side elevation of the wing cams as indicated at arrow 4, Figures 1 and 2.

The improved cam head, which forms the 40 subject matter of this application, comprises a disk 10 rigidly connected with the tubular shaft 11, providing an opening 12, to insert a rigid shaft to support the dial beneath 45 the dial head, permitting the dial head to rotate while the dial remains stationary. The mechanism for driving the dial head and for supporting the dial is not shown as it is well known in the art.

The disk 10 is provided with guide ways 50 13 extending entirely across the face of the disk in which are mounted to slide radially, blocks 14 and 15. The blocks 14 and 15 are provided with pins 16 which extend upwardly through slots 17 and 18, and to such dis-

tance above the upper plane of the disk as may be necessary to attach the controlling mechanism as, for instance, such distance as indicated at Figure 3. Mechanism is provided for attaching to the pins 16 to move 60 such pins radially and therewith the blocks 14 and 15, as the exigencies of the knitting may make necessary, but being well known is not here shown.

The block 14 is provided with a groove 65 19, separating the periphery of such block from the cam 20 carried thereby. Preferably the peripheral rib or guard cam and the cam 20 will be integral, the groove 19 simply being cut in the face of the block. The 70 peripheral rib is also cut down at 21 and a curvilinear cam member 22 hinged thereto as at 23. The cam member 22 is substantially S-shaped with the end opposite the pivot 75 23 slidable in the groove 24 cut in the cheek of the disk 10, the end of the cam 22 being reduced as at 25 so as not to interfere with the needle latches when projected as in Figure 2.

The block 15 is likewise provided with 80 a groove 26 defining a cam member 27. The cam 27 also being carried integral with the block 15. The cam members 20 and 27, as will be noted, are approximately semi-circular and when moved apart as, for instance to the position shown at Figure 1, define parts of an ellipse. An elliptical cam 85 way is desirable for actuating the dial needles, and to permit the elliptical cam to be elongated as found necessary, means is 90 provided for completing the ellipse. The means provided are wing cams, consisting of the members 28 and 29 upon one side, and 30 and 31 upon the other side. The two sets 95 of wing cams, although slightly different in shape because of the requirements for guiding the needles, are sufficiently identical so that a description of one set of wing cams will define the other. The wing cams 30 and 31 are hinged together, preferably by being 100 halved as at 32 (see Figure 34) with a pintle 33 inserted through the halved sections as a hinge. The pintle 33 engages a supporting member 34, preferably in form of a screw having a threaded portion 35, 105 which engages a properly threaded opening in the disk 10. The supporting member 34 holds the wings 30 and 31 properly spaced from the back of the disk 10 to pass into the grooves 26 and 19, and to permit a spring 110

36 to engage upon the pins 37 and 38 for exerting tension on the wings to hold the points in intimate contact with the cams 20 and 27.

5 A cam finger or guard cam 39 is also preferably secured to one of the cheeks of the disk 10 with a guard cam upon the opposite side, comprising the sections 40 and 41 with a movable block 42 intermediate sections 40 10 and 41. The last mentioned cam considered in its entirety, forming a continuation with the movable cam 22, corresponds to the cam member 39 except that one section 22 of the cam is made movable.

15 The movable section 42 is attached to a pin 43, which extends upwardly through the disk 10 and is pivoted to a lever 44 fulcrumed at 45 with a spring 46 tending to normally hold the section 42 in position 20 to complete the cam. By depressing the lever 44 the section 42 is raised into the disk 10, opening a passage for the withdrawal of one of the dial needles for replacing such dial needles as occasion may require.

25 As shown at Figures 1 and 2 a flight of small arrows indicates the adjustable cam groove to receive and actuate the shanks of the dial needles. The direction indicated by the arrows is the relative direction of movement 30 of the cam needles, it being understood of course that the cam needles do not themselves rotate, but that the cam groove with the cams and cam heads are the rotating part, the cam head rotating in the direction 35 indicated by the circumferential arrows producing the relative movement indicated by the flight of small arrows within the groove. It will also be understood that the cam 20 and its surrounding adjacent parts is the cam 40 which actuates the dial needles for knitting, while the cam 27 and its surrounding adjacent parts is the cam which advances the dial needles for stripping.

Having thus fully described my said invention, what I claim as new and desire to 45 secure by Letters Patent, is:

1. A dial cam mechanism comprising a dial cap, cams movable radially upon the cap and presenting each a portion of an 50 ellipse, adjustable cam members spanning the interval between the first mentioned cams, and an external cam member pivotally connected with one of the first mentioned cam members and movable therewith.

55 2. A dial cam mechanism comprising a dial cap having blocks mounted to move diametrically thereon and each comprising an external rib and an internal cam portion forming a part of an ellipse, spring pressed 60 members spanning the interval between and engaging the sides of the elliptical cam members, and a cam member hinged to one of the external ribs and movable with the block.

65 3. A dial cam mechanism comprising a dial cap having blocks movable radially

relative thereto, external arcuate ribs formed upon the outer extremities of the blocks, internal cam members formed upon the blocks defining a cam groove between the cam members and the ribs, wings pivoted 70 between the cam members and having their extremities bearing yieldingly upon the sides of the cam members, and a curvilinear cam member having one end pivoted to one of the external ribs and the other end slidable 75 in a fixed portion of the dial cap.

4. A dial cam mechanism comprising a cap having diametrical slots formed therein, blocks mounted to slide diametrically upon the cap pins on the blocks extending through 80 the slots, external ribs formed upon the outer ends of the blocks, internal cam members spaced away from the external ribs defining a cam groove between, cam wings pivoted between the cam members and having their 85 extremities bearing yieldingly upon the sides of the cam members, a protective cam finger mounted rigidly at one side of one of the blocks, and a curvilinear cam member having one end pivoted to one of the external ribs 90 and the opposite end slidable in a fixed portion of the dial cap at one side of one of the sliding blocks.

5. A dial cam mechanism comprising a dial cap having diametrical slots formed 95 therein, blocks mounted upon the face of the cap slidable diametrically relative thereto, connecting members extending from the blocks through the slots, inner and outer cam members carried by the blocks forming 100 cam grooves conforming substantially with parts of an ellipse, cam wings pivoted between the blocks and having their extremities bearing upon the sides of the inner cam members and completing the ellipse adjustable in length by the movement of the blocks one of said outer cam members having a reduced portion, and a curvilinear cam member pivoted in said reduced portion and making sliding connection with a fixed part 110 of the dial cap.

6. A dial cam mechanism comprising a dial cap, a cam block slidable radially relative to the dial cap and providing an outer rib and an inner cam member defining a cam groove there between, said outer rib being cut away in part, a curvilinear cam member having one end pivoted at the cut-away portion of the rib, and a sliding extremity formed upon the opposite end of the curvilinear member making sliding engagement with a fixed part of the dial cap.

7. In a dial cap for rib knitting machines, a pivoted needle retracting cam having an opening, a radially movable needle projecting cam and a pivot pin fitting in the opening in the needle retracting cam and movable with the needle projecting cam, substantially as set forth.

8. In a dial cap for rib knitting machines,

an elongated needle retracting cam having one end slidably connected to the cap, a pivot for said cam movable radially of the dial cap, and needle projecting and guard cams 5 cooperating with the needle retracting cam and also movable on the dial cap, substantially as set forth.

9. In a dial cap for rib knitting machines, knitting means comprising a needle projecting cam adjustable to vary the projection of the needles to cause them to take or reject the yarn, a needle retracting cam movable with and independently of the needle projecting cam, the needle projecting cam 10 falling off sharply at the side next to said retracting cam and the latter when in knitting position lying close to that side of the

needle projecting cam, thereby providing for abrupt retraction of the needles, substantially as set forth. 20

10. In a dial cap for rib knitting machines having a cam path for the needle-butts, radially movable blocks, inner and outer cams thereon, fixed cams on the cam cap between said blocks, a gate-way in one 25 of said blocks for removal of broken needles, and a lever at the opposite side of the cap for opening the gate, substantially as set forth.

In witness whereof, I have hereunto set 30 my hand and seal at Washington, District of Columbia this 20th day of November, A. D. nineteen hundred and nineteen.

NAPOLEON J. PERRY. [L. s.]
